UNITED STATES PATENT OFFICE.

FRANKLIN FOSTER, OF WOODWARD, MICHIGAN.

WIRE-STRETCHING DEVICE.

SPECIFICATION forming part of Letters Patent No. 597,059, dated January 11, 1898.

Application filed May 5, 1897. Serial No. 635,152. (No model.)

To all whom it may concern:

Be it known that I, FRANKLIN FOSTER, a citizen of the United States, residing at Woodward, in the county of Wayne and State of Michigan, have invented certain new and useful Improvements in Wire - Straining Devices, of which the following is a specification, reference being had therein to the accompanying drawings.

- o This invention relates to that class of wire-stretchers designed for use in building wire fences; and the object is to furnish to the fence-builder a simple, light, and inexpensive tool for stretching the wire along the posts preparatory to securing it to the posts.

To this end my invention consists of the peculiar construction, arrangement, and combination of a fulcrum-bar, an operating-lever, and straining and retaining wire-clamps, all as more fully hereinafter described, and shown in the accompanying drawings, in which—

Figure 1 is a perspective view of my improved tool, illustrating it as in operation; Fig. 2 is a plan of the device as in operation; and Fig. 3 is a fractional perspective of the device, showing the parts in different position from that in Fig. 1.

A is a fulcrum-bar provided with an arm B, extending therefrom at right angles, or 30 nearly so.

C are prongs secured to or formed on the bar A.

D is a lever pivotally secured upon the fulcrum-bar at E.

35 F is a standard on the free end of the arm B and carrying the retaining clamp-dog G, which is pivotally secured thereto, and H is a lug for guiding the wire beneath the clamp G.

The lever D has pivotally secured at N 40 near its fulcrum a bed-plate I, formed with a standard J, carrying the straining clamp-dog K, and with a lug for guiding the wire beneath said dog.

In practice, the parts being constructed and 45 arranged as described, they are intended to operate as follows: The fulcrum-bar is abutted against the side of the post with the arm B extending in line with the wire to be stretched, as shown in Fig. 1. The wire M is 50 then passed beneath the dog G and beneath the dog K, with the lever D extending in line

with the bar A. If the dog K is then tightened down, it firmly clamps the wire, and, drawing the lever in the direction as shown in Fig. 2, the wire is strained. If the lever is now released, the dog G will firmly clamp the wire and retain it in position in order to obtain a new hold upon the wire with the clamp K, for the purpose of straining it still further, if required. I preferably make the fulcrum-bar A and arm B integrally of one piece of flat steel bar and make the angle between the two preferably less than ninety degrees, so that the wire will always be drawn up against the face of the post to which it is to be secured. Furthermore, I make slight bends in the bar at a and b to form an offset portion whereby the wire is lifted sufficiently above the arm B to permit of the convenient driving of a staple to fasten the wire. I also provide the arm D with a slight bend at c for the purpose of bringing the fulcrum E, pivot N, bed-plate I, and free end of the arm B all in horizontal plane with each other for the purpose of getting a straight pull on the wire. 75

The object of pivoting the bed-plate I upon the lever D is to allow it to adjust itself in line with the wire during the operation of the lever, and by this means it will be seen that the stretching of the wire is accomplished 80 without producing any kinks or bends in it, and not a particle of the fence-wire is wasted.

What I claim as my invention is—

1. In a wire-stretcher, the combination of a fulcrum-bar, an arm extending forwardly 85 at an angle to the fulcrum-bar, an automatic clamp at or near the forward end of the said arm, an operating-lever fulcrumed to the fulcrum-bar, and an automatic clamp pivotally secured to the operating-lever and provided 90 with means for retaining it in proper relation to the wire, substantially as described.

2. The combination of the fulcrum-bar provided with an arm extending therefrom at substantially a right angle, a wire - guide 95 formed at the free end thereof, a dog pivotally mounted above the same and forming in connection therewith an automatic retaining-clamp, an operating-lever fulcrumed upon the fulcrum-bar, a swinging wire-guide pivotally 100 mounted upon the operating-lever and a dog pivotally mounted upon said wire-guide and

forming in connection therewith a straining-clamp.

3. In a wire-stretcher, the combination of the pronged fulcrum-bar A, provided with the 5 arm B and bends a and b, the standard F thereon carrying the retaining-dog G, the guide-lug H, the operating-lever D, the swinging bed-plate I provided with the lug L and standard J, and the straining-dog K pivotally 10 secured thereto.

4. In a wire-stretcher, the combination of an angular fulcrum-bar provided with an offset portion, a clamp on the bar at one side of 15 said offset portion, an operating-lever fulcrumed to the fulcrum-bar on the opposite side of the offset portion, and a clamp carried by said lever, substantially as described.

5. In a wire-stretcher, the combination of 20 a fulcrum-bar, an arm extending forwardly at an angle thereto, a standard at or near the

forward end of said arm, a retaining-dog carried by said standard, an operating-lever fulcrumed to the fulcrum-bar, a pivoted plate carried by the lever, a standard on said plate, and a retaining-dog carried by said standard, 25 substantially as described.

6. In a wire-stretcher, the combination of an arm, a bar for holding said arm to a support such as a fence-post, an automatic clamp at or near the forward end of said arm, an 30 operating-lever fulcrumed to said bar, and an automatic clamp carried by said operating-lever and adapted to clamp the wire in any position of the lever.

In testimony whereof I affix my signature 35 in presence of two witnesses.

FRANKLIN FOSTER.

P. M. HULBERT.

Correction in Letters Patent No. 597,059.

It is hereby certified that the residence of the patentee in Letters Patent No. 597,059, granted January 11, 1898, upon the application of Franklin Foster, for an improvement in "Wire-Stretching Devices," was erroneously written and printed "Woodward, Michigan;" that said residence should have been written and printed *Woodmere, Michigan*; and that the said Letters Patent should be read with this correction therein that the same may conform to the record of the case in the Patent Office.

Signed, countersigned, and sealed this 18th day of January, A. D., 1898.

[SEAL.]

WEBSTER DAVIS,
Assistant Secretary of the Interior.
